US0D1013330S

(12) **United States Design Patent** (10) **Patent No.:** **US D1,013,330 S**
(45) **Date of Patent:** **** Feb. 6, 2024**

(54) **HEATING VEST**

(71) Applicant: **Yue Li, Guangdong (CN)**

(72) Inventor: **Yue Li, Guangdong (CN)**

(**) Term: **15 Years**

(21) Appl. No.: **29/911,929**

(22) Filed: **Sep. 11, 2023**

(51) **LOC (14) Cl.** **02-02**

(52) **U.S. Cl.**

USPC **D2/829**

(58) **Field of Classification Search**

USPC D2/717, 750, 829, 731, 828; D29/101.4

CPC A41D 1/04

See application file for complete search history.

(74) *Attorney, Agent, or Firm* — Hawaii Patent Services; Nathaniel K. Fedde; Kenton N. Fedde

(57) **CLAIM**

The ornamental design for a heating vest, as shown and described.

DESCRIPTION

FIG. 1 is a front perspective view of a heating vest, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a front perspective view of the heating vest in an opened state; and,

FIG. 8 is a rear perspective view of the heating vest in an opened state.

(Continued)

The dashed broken lines in the figures are for the purposes of illustrating portions of the heating vest, which form no part of the claimed design.

1 Claim, 8 Drawing Sheets
